FRED M. YOUNG, OF RACINE, WISCONSIN.

SECTIONAL RADIATOR.

Application filed April 21, 1927. Serial No. 185,426.

This invention relates to heat inter-changers and more particularly to an improved form of sectional radiator for internal combustion engines.

- 5 The main objects of this invention are to provide in a sectional radiator, an improved form of joint between the headers and their companion tanks; and, to provide an improved arrangement of communicating means between the several headers and the upper and lower tanks, which arrangement is adapted to permit a freer flow of the cooling medium between the headers.
- 10

In prior forms of sectional radiator construction, the several core units have each been provided with upper and lower headers, which headers have stepped scarf joints for coacting with a similar stepped scarf joint of the upper and lower tank. Each header 15 has also been provided with a port through its stepped scarf joint registering with a port in the coacting stepped scarf joint of its companion tank. Because of the narrow width of such stepped scarf joints, it has 20 been impossible to provide a port whose orifice is of sufficient width to permit a free flow of the cooling medium between the tanks and their communicating headers; moreover, the flow of the cooling medium between the 25 tanks and the headers is further restricted by virtue of the fact that the current of the cooling medium is forced to flow in a more or 30 less tortuous path.

In the present invention, the upper and 35 lower headers each have a comparatively wide angularly disposed shoulder and each shoulder is provided with a port. The top and bottom tanks each have an angularly disposed shoulder coacting with the angularly 40 disposed shoulders of the several headers. The angularly disposed shoulder of each tank is provided with a plurality of ports registering with the ports of the companion headers. Because of the comparatively wide 45 angularly disposed shoulder of the top and bottom tanks and the width of the coacting shoulders of the several headers, it is possible to provide ports having orifices of greater width, thereby providing a freer flow of the 50 cooling medium between the tanks and headers of the several core units. Moreover, the disposition of the coacting angularly disposed shoulders is such that the current of flow between the tanks and the headers of 55 the several core units is more direct and less tortuous than the current of the cooling me-

dium in radiators having scarf joint connections.

An illustrative embodiment of the invention is shown in the accompanying drawings 60 wherein:

Fig. 1 is a fragmentary front elevation of a sectional radiator for internal combustion engines, a portion thereof being broken away.

Fig. 2 is an end view thereof taken on line 2—2 of Fig. 1.

Fig. 3 is a fragmentary sectional view thereof taken on line 3—3 of Fig. 2.

In the drawings, the radiator has the usual 70 upper tank 1 and the lower tank 2 secured together by the vertically disposed side supporting frame members 3. The upper tank is provided with the usual threaded filler neck 4 on which a closure cap 5 is screwed. 75

A series of elongated vertically disposed core units 6 are provided and each unit comprises a plurality of vertically disposed water tubes 8 which communicate with upper and lower headers 9 and 9^a respectively. The 80 core sections are provided with a plurality of horizontally disposed radiating fins 7. Each of the several headers 9 and 9^a have an angularly disposed shoulder 10 inclined relatively to the horizontal and each shoulder is 85 provided with a rectangular port 11. The top and bottom tanks 1 and 2 each have a similarly disposed shoulder 12 coacting with the inclined shoulders of its companion headers and each shoulder 12 is provided with a 90 plurality of rectangular ports 13 registering with their companion header ports 11.

Means for securing each of the several headers with their upper and lower tanks comprises bolts 14 which pass through integrally formed tubular members 16 of the headers and tanks and at an angle approximately the transverse of the angle of the coacting shoulders.

The transaqueous passageways furnished 100 by the diagonal tubes 16 dry-house the bolts 14, and so protect them against rust and consequent weakening.

The arrows in Fig. 2 indicate the flow of 105 the cooling medium from the inlet through the upper hose connection 15 into the top tank and through the registering communicating ports 11 and 13 into the upper headers 9, thence downwardly through the vertically disposed water tubes to the lower headers 9^a, 110 through the registering communicating ports of the lower headers and the bottom tank,

for circulation to the engine through the lower hose connection 17.

It will thus be seen that the improved form of sectional radiator provides communicating ports between the headers and their companion tanks so arranged that the flow of the cooling medium from the headers to the tanks is less restricted because it is possible to provide ports of greater size.

10 While but one specific embodiment of this invention has been shown and described, it will be understood that numerous details of the construction shown may be altered or omitted without departing from the spirit of 15 this invention as defined by the following claims:

I claim:

20 1. A radiator of the class described comprising an upper tank, a lower tank in spaced relation to said upper tank, a core unit for providing communication between said tanks, coacting inclined shoulders on said tanks and unit, said shoulders having registering ports therein, and bolts extending through said unit and tanks disposed transversely to said inclined shoulders for securing said unit to said tanks, the latter having inclined fluid-tight transaqueous passageways extending to an elevated position in the back to accommodate 30 said bolts with dry housing.

2. A sectional radiator of the class described comprising an upper tank, a lower

tank in spaced relation to said upper tank, a series of core units for providing communication between said tanks, a top and a bottom header on the top and bottom ends of said units respectively, the under side of said upper tank having a horizontal surface and an upwardly inclined surface providing a shoulder, said inclined surface having ports 35 therein, said bottom tank having a horizontal upper surface and a downwardly inclined surface providing an inclined shoulder, said inclined shoulder having ports therein, said sectional unit top and bottom headers having 40 surfaces which conform to said upper and lower tank surfaces respectively and having surfaces which register with the ports 45 in their respective upper and lower tanks, and a plurality of bolts, one at each edge of each header, and passing through the upper headers and upper tank and through the lower headers and lower tank for securing said sectional units to said upper and lower tanks, said bolts being disposed transversely to the 50 inclined shoulders on said upper and lower tanks and headers, said tanks having transaqueous tubular passageways to dry-house 55 said bolts, which passageways are horizontally flattened to accommodate each a pair of 60 said bolts.

Signed at Chicago this 18th day of April, 1927.

FRED M. YOUNG.
